APPROACH CONTROL APPARATUS FOR
RAILWAY SIGNALING SYSTEMS

Herman G. Blessner, Pittsburgh, Pa., assignor to
The Union Switch & Signal Company, Swiss-
vale, Pa., a corporation of Pennsylvania

Application August 12, 1938, Serial No. 224,564

8 Claims. (Cl. 246—38)

My invention relates to approach control apparatus for use in railway signaling systems of the coded track circuit class and it has special reference to the employment of such apparatus for approach controlling various signaling functions without the use of line wires.

Generally stated, the object of my invention is to improve certain features of an approach control without line wire scheme wherein the rails of each unoccupied signal block length of track transmit code step pulses of auxiliary energy forwardly from the block entrance to effect the energization of a slow release approach relay at the block exit.

15. A more specific object is to supply the referred to pulses of auxiliary energy to the entrance end of each track circuit in a simplified manner which avoids interference with the normal code following operation of the signaling system track relay at that location.

In practicing my invention I attain the above and other objects and advantages by supplying the auxiliary energy from a low voltage battery which is interposed between the rails and the 25. signaling system track relay connected thereto; by poling this battery in opposition to the higher voltage track battery which supplies the exit end of the signaling system track circuit with the usual coded energy by which the track relay is 30. operated; and by rendering that relay unresponsive to energy from this auxiliary battery.

I shall describe two forms of approach control apparatus embodying my invention, and shall then point out the novel features thereof in 35. claims. These illustrative embodiments are disclosed in the accompanying drawing in which:

Fig. 1 is a diagrammatic representation of a single section of railway track which is equipped with my improved approach control apparatus; 40 and

Fig. 2 is a partial representation of a modified form of exit end facilities which are usable with the approach control scheme of Fig. 1.

In the two views of the drawing, like reference 45 characters designate corresponding parts. Referring first to Fig. 1, the improved approach control apparatus of my invention is there disclosed in association with a coded track circuit system of automatic block signalling for a rail-way track 1—2 over which it will be assumed that traffic moves in the single direction indicated by the arrow, or from left to right in the diagram. The protected stretch of this track is divided into the customary successive sections by insulated rail joints 3 and the rails of each section

form a part of a track circuit to which coded signal control energy is supplied in customary manner.

In this view of Fig. 1, reference characters D and E respectively designate the entrance and the exit ends of one of these track sections which is illustratively shown as being a full signal block in length; character TR designates a code following track relay which is installed at the entrance end of the section and operated by energy 10 received from the rails thereof; character TB a track battery or other direct current source provided at the section exit for the purpose of supplying these rails with the relay operating energy just referred to; character CR a coding device having a contact 5 which codes this energy by periodically interrupting the rail supply circuit; and character S the usual wayside signal which guards the entrance of each of the track blocks and which is controlled by the associated 20 track relay TR through the medium of decoding apparatus 10.

An automatic block signalling system of the referred to coded track circuit type operates without the aid of line wires and in representative 25 form it includes all of the elements above named. Such a system further comprises the customary facilities (not shown) for continuously operating each of the exit end relays CR at one or another of the usual plurality of distinctive code rates. 30 Selection among these rates (which in a typical three indication system may consist of 80 and 180 energy pulses per minute) is made in accordance with advance traffic conditions by the decoding apparatus 10 functioning in customary manner. 35

This decoding apparatus (details not shown) is controlled in the usual fashion by the associated track relay TR and it performs the further function of selectively setting up a lighting circuit for one or another of the lamps (G, Y and R in 40 the typical three indication system above referred to) of the wayside signal at the same location. In the arrangement represented, these signal lamps derive energizing current from a power source which is designated by the terminals 45 "plus" and "minus."

In order that certain functions of the signalling system may be rendered active only upon the approach of a train, the apparatus installed at each of the signal locations D, E, etc., is supplemented by an approach relay AR which is arranged to maintain the referred to functions inactive at all times except when the section of track to the rear of the location becomes occupied. In the illustrative arrangement which is 55

shown at location E in Fig. 1, only one such function is approach controlled and this consists in lighting the wayside signal Se.

For governing the approach lighting function 5 above stated, the approach relay AR is provided with a contact 9 over the back point of which the signal lighting circuits are carried. As will become apparent as the description proceeds, this or companion contacts of the relay AR also may 10 be utilized to approach control signaling functions other than or in addition to the one just named. Typically, one such further function may consist in supplying the rails of the track section to the rear of the approach lighted signal 15 with coded alternating current energy which is suitable for the control of train carried cab signals (not shown).

When applied to coded signaling systems of the conventional character just considered, the 20 improved approach control apparatus herein disclosed renders the relay AR at each signal location responsive to the approach of a train and does this, moreover, without the use of control line wires. In the form shown in association with 25 the signal block D—E of Fig. 1, this apparatus comprises: (1) entrance end facilities which supply the rails of that block with pulses of auxiliary energy which are in step with recurring periods of the main signal control code and (2) exit end 30 facilities which receive these auxiliary pulses from the rails and energize the approach relay AR in step with them.

As represented at location D, my improved entrance and facilities make use of a direct current 35 source of auxiliary energy which is represented as a battery AB. This battery has a voltage which is substantially lower than that of the track battery TB at the section exit and it is connected between the rails of track section D—E 40 and the winding of the signaling system track relay TR which receives operating energy therefrom.

This connection is a serial one and it is so 45 made that the potential of battery AB opposes that of the higher voltage track battery TB whenever the latter is connected with the rails by coding contact 5. As a result, the current which this auxiliary battery AB at times circulates through the winding of track relay TR is 50 in a direction opposite to that of the relay operating current from battery TB. For preventing the track relay from responding to this auxiliary energy, it preferably is of a polarized design which cannot pick up in response to reverse flowing current from battery AB.

In the form shown at location E in Fig. 1, the 55 cooperating exit end facilities include means for connecting the winding of the approach relay AR in energy receiving relation with the rails 1 and 2 of the track section D—E during each "off" period of the signal control code (which the continuously operating device CR produces) and means for making this relay AR sufficiently slow releasing to bridge the intervals between successive connections thereof with the track rails. The first named means consists in carrying the relay winding circuit over the back point of the coding contact 5; the second named or delay producing means may, of course, take any suitable form, such as a snubbing impedance (not shown) bridged across the winding terminals or internal design expedients (again not shown) incorporated in the relay.

In operation of the complete approach control system of Fig. 1, the track rails 1 and 2 of

section D—E act in the usual manner to transmit energy from one end of the section to the other as long as the section remains unoccupied. Each time, under such conditions, that contact 5 of the coding device CR is in the uppermost or "on" 5 code period position, the track battery TB picks up the track relay TR over a circuit which may be traced from the positive terminal of the battery through a current limiting impedance 13, conductor 14, track rail 1, conductor 15, the open 10 position connected low voltage battery AB, conductor 16, the winding of relay TR, conductor 17, track rail 2, conductor 18 and front contact 5 of device CR back to the negative terminal of battery TB. 15

As previously stated, the potential of the auxiliary battery AB is substantially less than that of the signaling system track battery TB. For example, while battery AB may consist of a single primary cell, battery TB preferably will be 20 made up of two, three or even four of such cells, thereby not only completely overcoming the opposing voltage of battery AB but providing at all times sufficient excess normal polarity potential to pick up the track relay TR each time that 25 the coding contact 5 is in the uppermost or "on" period position.

Each time that this contact occupies the lowermost or "off" code period position, the track relay TR releases. Again this release takes place 30 in normal manner and is undelayed by the reverse flowing current with which the auxiliary battery AB supplies the track rails during the "off" periods. As already mentioned, relay TR preferably is a device having polarized response characteristics and in that event it is adapted to pick up only when the left terminal thereof is made positive with respect to the right terminal.

With the particular connections which are shown in Fig. 1, this happens each time that coding contact 5 connects the track battery TB with the rails and makes rail 1 positive with respect to rail 2. Considering the auxiliary battery AB, it will be seen that while it also tends to make rail 1 positive with respect to rail 2, it can circulate current through the winding of relay TR 45 only in the reverse direction. The effect of such reverse current is not to pick up the relay contacts but rather to urge them more positively into their fully released positions. 50

Each "off" period or lowermost position of the coding contact 5 connects the winding of the slow release approach relay AR in energy receiving relation with the track rails 1 and 2 and thus impresses upon it the voltage at which the auxiliary battery AB maintains these rails during the "off" periods of the signal control code. During each of such periods this battery AB supplies relay AR with a pulse of energizing current over a circuit which may be traced from the positive 60 terminal of the battery through conductor 15, track rail 1, conductor 14, the winding of relay AR, conductor 20, back contact 5 of device CR, conductor 18, track rail 2, conductor 17, the winding of relay TR and conductor 16 back to 65 the negative terminal of battery AB.

As long as the track section D—E remains vacant, therefore, the operating winding of the approach relay AR is energized in step with each "off" period of the signal control code over the 70 circuit just traced. Because of its slow releasing characteristics the relay now holds its contact 9 continuously picked up and thereby maintains the lighting circuits of the wayside signal Se disconnected from their energizing source. In 75

this manner the approach controlled signaling function just named is continued inactive as long as the track section remains vacant.

In the event, now, that a train comes into the section D—E, the usual shunting action of its wheels and axles cuts off the transmission over the rails 1 and 2 of energy from battery TB to relay TR and also of energy from the auxiliary battery AB at the section entrance to the approach relay AR at the section exit. Now continuously deenergized, this approach relay releases and contact 9 thereof completes the energizing circuit for the signal Se. In consequence, that signal lights the particular lamp selected by the decoding equipment 10.

As soon as the rear of the departing train clears location e, the track circuit again transmits coded direct current energy to the track relay TR at location D, auxiliary battery AB again supplies the track rails with low potential energy during the "off" periods of the signal control code, these rails transmit this auxiliary energy forwardly to location E and the there located approach relay AR receives the recurring pulses of this energy over coding contact 5 of device CR. In again picking up in response to these pulses, contact 9 of relay AR restores the associated wayside signal Se to its normally inactive state.

Referring now to Fig. 2, I have there represented a somewhat modified form of exit end facilities which may be used in place of the apparatus represented at E in Fig. 1. These are generally equivalent to the corresponding facilities earlier described and in considering them it will be helpful to assume that the conductors 14 and 18 of Fig. 2 are joined at location E with the track rails 1 and 2 of Fig. 1 which extend rearwardly to location D of the same figure where they are connected with track relay TR and auxiliary battery AB.

The modified facilities of Fig. 2 differ, however, from those in Fig. 1 in that a sensitive code following detector relay KR is interposed between the track rails and the slow release approach relay AR in a manner similar to that disclosed and claimed by each of the following copending applications: Serial No. 218,923, filed July 3, 1938, by Charles B. Shields; Serial No. 220,015, filed July 19, 1938, by Crawford E. Staples; Serial No. 221,317, filed July 26, 1938, by Edward U. Thomas; Serial No. 222,014, filed July 29, 1938, by Herman G. Blosser; and Serial No. 223,076, filed August 4, 1938, by Herman G. Blosser. This added relay KR performs two functions. First, it increases the sensitivity of the exit end apparatus and thereby enables the approach relay to respond to comparatively weak pulses of auxiliary energy which may be received from the track circuit. Second, it insures that the approach relay AR cannot be continuously energized from the auxiliary battery AB in the event that the coding contact 5 is stopped in the lowermost or "off" code period position.

From a comparison of the diagrams of Figs. 1 and 2 it will be seen that the winding of detector relay KR of Fig. 2 is connected by coding contact 5 with the track rails 1 and 2 during each "off" period of the signal control code in the same manner as is the winding of relay AR in Fig. 1. Instead of being slow releasing, however, this interposed detector relay is quick acting in both the pick-up and the drop-out directions and in consequence its contact 22 picks up upon the occasion

and for the duration of each of the pulses of auxiliary energy which the winding of the relay receives from the auxiliary battery AB at the entrance end of the section. Between pulses, of course, relay KR releases in the usual code following manner.

Controlled by this contact 22 of relay KR is an energizing circuit for the winding of the associated approach relay AR which circuit is shown as being identified with local power supply terminals "plus" and "minus" and which includes a transformer AT. With the arrangement of devices KR, AT and AR that is shown in Fig. 2 (which arrangement embodies principles that are disclosed and claimed in a copending application Serial No. 210,744, filed May 28, 1939, by Frank H. Nicholson et al.) the recurring auxiliary energy pulses from the battery AB act through relay KR to cause the local source just referred to to supply similarly timed pulses of energizing current to the relay AR.

As in the case of Fig. 1, this approach relay AR is provided with a contact 9 which controls the energizing circuit for the associated wayside signal S (not shown in Fig. 2). As in the case of Fig. 1 also, the relay AR has slow releasing characteristics imparted thereto by any suitable means, such as the use of a snubbing element (again not shown) or internal design expedients.

In operation of the exit end facilities of Fig. 2, each time, under vacant conditions of the track section (see D—E of Fig. 1), that contact 5 of the coding device CR is in the uppermost or "on" period position, the track battery TB supplies the rails with energy for picking up the track relay TR (see location D of Fig. 1) in the same manner as in Fig. 1. Each time, likewise, that the coding contact 5 occupies the lowermost or "off" period position, the winding of relay KR is connected in energy receiving relation with the rails and has impressed thereon a pulse of auxiliary energy from battery AB (again see location D of Fig. 1). As will be evident from the diagram, this energy supply is over conductors 14 and 18 and back contact 5.

In receiving these recurring pulses of auxiliary energy, the detector relay KR at the section exit responds to them in code following manner. In so responding that relay causes contact 22 thereof to pole change the primary circuit of the transformer AT which is interposed between the approach relay AR and the local direct current source with which the terminals "plus" and "minus" are identified. From this transformer output energy of code pulse frequency is supplied to the operating winding of relay AR over circuits which include a rectifying contact 23 of the detector relay.

As long as this recurrent energization of the slow release approach relay AR continues, that relay holds its contact 9 picked up and in this manner the wayside signal Se (see Fig. 1) is maintained inactive until a train comes into the associated section of track.

When that happens, the usual shunting action of the train wheels and axles cuts off the transmission through the rails 1 and 2 of the auxiliary energy to the detector relay KR and in consequence that relay releases continuously. This causes the approach relay AR to become deenergized due to the inability of the transformer AT to generate secondary voltage when its primary circuit is subjected to unvarying direct current. Contact 9 of relay AR accordingly releases and

thereby lights the associated wayside signal in desired manner.

As soon as the rear of the departing train clears the exit end of the associated track section the rails of that section again transmit "off" period pulses of auxiliary energy from the entrance end battery AB forwardly to the exit end detector relay KR. In once more responding, that code following device operates contacts 22 10 and 23 in the primary and secondary circuits of transformer AT and thereby causes the associated slow release approach relay AR again to be energized. The approach relay once more picks up and in so doing restores the associated 15 wayside signal to its normally inactive condition.

From the foregoing it will be seen that I have provided simplified and otherwise improved entrance end facilities for an approach control without line wire scheme wherein use is made of 20 forwardly fed pulses of auxiliary energy which are supplied to the track circuit during the "off" periods of the main signal control code. As these facilities are entirely a function of the track circuit and apparatus which is directly associated 25 therewith, they are independent of the coding and decoding apparatus of the coded signaling system with which they are combined and hence they are usable with signaling systems which employ a wide variety of different types and 30 forms of such apparatus. Moreover, while I have explained my invention in an application wherein the lights of the wayside signal only are approach controlled, it will be understood that other 35 comparable functions may also be provided for instead of or in addition to the illustrative one just named.

Although I have herein shown and described only two forms of approach control apparatus 40 embodying my invention, it will be understood that various changes and modifications may be made therein within the scope of the appended claims without departing from the spirit and scope of my invention.

45 Having thus described my invention, what I claim is:

1. In combination with a section of railway track, a source of signal control energy at the exit end of said section, similarly located means 50 for recurrently connecting said source with the section rails whereby to produce a signal control code consisting of alternate "on" and "off" periods, a code following track relay which is responsive to given polarity current but not to 55 opposite polarity current, a circuit so connecting the winding of said track relay across said rails that the said coded signal control energy which is received from those rails passes given polarity current through said winding and thereby operates the relay, a source of auxiliary energy having a voltage which is substantially less than that of 60 said exit end signal control source and being serially included in said track relay winding circuit in polarity opposing relation to the energy 65 of said received signal control code whereby to supply a pulse of auxiliary energy to said rails during each "off" period of that received code and to do this without falsely operating the track relay, a slow release approach relay located at 70 the section exit and energized in step with the said recurring pulses of auxiliary energy which are there received from said rails whereby to be maintained continuously picked up as long as said section is vacant and to release only when 75 a train comes into the section, and traffic gov-

erning apparatus controlled by said approach relay.

2. In combination with a section of railway track, a source of direct current signal control energy at the exit end of said section, similarly located means for recurrently connecting said source with the section rails whereby to produce a signal control code consisting of alternate "on" and "off" periods, a code following track relay which is responsive to given polarity current but not to opposite polarity current, a circuit connecting the winding of said relay across said rails in such manner that the said coded signal control energy which is received from those rails passes given polarity current through said winding and thereby operates the relay, an auxiliary source of direct current energy having a voltage which is substantially less than that of said signal control source and being serially included in said track relay circuit in polarity opposing relation to the energy of said received signal control code whereby without falsely operating the track relay to supply a pulse of auxiliary energy to said rails during each of the said "off" periods of that received code, a slow release approach relay at said section exit, similarly located means controlled by said recurring pulses of auxiliary energy which are received from said rails for energizing said approach relay in step with those received pulses whereby to maintain the approach relay 30 continuously picked up as long as said section is vacant and to allow that relay to release only when a train comes into the section, and traffic governing apparatus controlled by said approach relay.

3. In combination with a section of railway track, a source of direct current signal control energy at the exit end of said section, a similarly located coding device which recurrently connects said source with the section rails and thereby produces a signal control code consisting of alternate "on" and "off" periods, a code following track relay which can be picked up by given polarity energy but not by opposite polarity energy, a circuit connecting the operating winding 45 of said track relay across said rails in such manner that the said coded energy which the winding receives from those rails has said given polarity and picks up the relay during each "on" period of the received signal control code, an auxiliary 50 source of direct current energy having a voltage substantially lower than that of said signal control source and being serially included in said track relay circuit in a manner to oppose the said signal control energy which the winding of said 55 track relay receives from said rails whereby without falsely picking up the track relay to supply a pulse of auxiliary energy to those rails during each "off" period of the received signal control code, a slow release approach relay located at the 60 section exit and energized in step with the said recurring pulses of auxiliary energy which are there received from said rails whereby to be maintained continuously picked up as long as said section is vacant and to release only when 65 a train comes into the section, and traffic governing apparatus controlled by said approach relay.

4. In combination with a section of railway track, a source of signal control energy at the exit end of said section, a similarly located approach governing relay, a coding device having a contact which repeatedly connects the rails of said section first to said energy source and then to the winding of said relay and thereby produces a signal control code consisting of alternate 70

- "on" and "off" periods the latter of which coincide with said relay winding connections, a code following track relay connected in energy receiving relation with said rails and being arranged to respond to the said coded signal control energy which is received therefrom but not to energy which is of opposite polarity, a source of auxiliary energy having a voltage which is substantially less than that of said signal control source and being serially included in said track relay connection in polarity opposing relation to the signal control source whereby under vacant conditions of said section to excite said approach governing relay over said rails during each "off" period of the said signal control code, and traffic governing apparatus controlled by said approach governing relay and rendered active when the said recurring excitation for that relay is cut off by the presence of a train in said section.
5. In combination with a section of railway track, a source of direct current signal control energy at the exit end of said section, a similarly located coding device which recurrently connects said source with the section rails and thereby produces a signal control code consisting of alternate "on" and "off" periods of given polarity energy, an approach governing relay also at the section exit, means controlled by said coding device for connecting said relay in energy receiving relation with said rails during each of the said "off" code periods, a code following track relay connected with said rails at all times and being arranged to respond to the said coded given polarity energy which is received therefrom but not to energy which is of the opposite polarity, an auxiliary source of direct current energy serially included in said track relay connection in polarity opposing relation to said signal control source whereby under vacant conditions of said section to excite said approach governing relay over said rails during each "off" period of the said received signal control code, and traffic governing apparatus controlled by said approach governing relay and rendered active when that relay becomes continuously deenergized in response to the presence of a train in said section.
6. In combination: a section of railway track, a source of direct current signal control energy at the section exit, means for recurrently connecting said source with the section rails whereby to produce a signal control code consisting of alternate "on" and "off" periods, a code following track relay which is responsive to given polarity energy but not to opposite polarity energy, an auxiliary source of direct current energy having a voltage which is substantially less than that of said signal control source, a circuit serially connecting the operating winding of said track relay and said auxiliary source across said section rails in such manner that each "on" period pulse of the said coded signal control energy which is received from those rails by said winding has said given polarity and picks up the track relay while the energy which said auxiliary source supplies to said rails during the "off" periods of the received code passes through the relay winding in the opposite polarity direction and does not operate the track relay, an approach governing relay at said section exit which is excited by the "off" code period pulses of said auxiliary energy that are there received under vacant conditions of said section, and traffic governing apparatus controlled by said approach governing relay and rendered active when that relay becomes continuously deenergized in response to the presence of a train in said section.
7. In combination with a section of railway track, a source of signal control energy at the section exit, a similarly located approach relay which has slow release characteristics, a coding device which repeatedly connects the rails of said section first to said energy source and then to the winding of said approach relay and thereby produces a signal control code consisting of alternate "on" and "off" periods the latter of which coincide with said relay winding connections, a code following track relay connected with said rails at the section entrance and arranged to respond to the said coded signal control energy which is there received from those rails but not to energy which is of opposite polarity, a similarly located source of auxiliary energy having a voltage which is substantially less than that of said signal control source and being serially included in said track relay connection in polarity opposing relation to the signal control source whereby to excite said slow release approach relay over said rails during each "off" period of the said received signal control code and thereby maintain that relay continuously picked up as long as said section is vacant, and traffic governing apparatus controlled by said approach relay and rendered active when that relay releases in response to the presence of a train in said section.
8. In combination with a section of railway track, a source of signal control energy at the section exit, a similarly located code following detector relay, a coding device which repeatedly connects the rails of said section first to said energy source and then to the winding of said detector relay and thereby produces a signal control code consisting of alternate "on" and "off" periods the latter of which coincide with said relay winding connections, a code following track relay connected with said rails at the section entrance and arranged to respond to the said coded signal control energy which is there received from those rails but not to energy that is of opposite polarity, a similarly located source of auxiliary energy having a voltage which is substantially less than that of said signal control source and being serially included in said track relay connection in polarity opposing relation to the said signal control source whereby to excite said exit and detector relay over said rails during each "off" period of the said received signal control code and thereby cause that relay recurrently to pick up under vacant conditions of said section, a slow release approach relay energized in step with the said recurrent pick-ups of the detector relay whereby to be maintained continuously picked up as long as said section remains vacant and to release only when a train comes into the section, and traffic governing apparatus controlled by said approach relay.

HERMAN G. BLOSSER.
